Application December 21, 1946, Serial No. 717,736

12 Claims. (Cl. 123—179)

1

The present invention relates to a control mechanism for internal combustion engines and more particularly to a control mechanism for starting internal combustion engines used in motor vehicles.

Modern motor vehicles are generally equipped with a fast idle arrangement and an automatic choke to provide an enriched fuel-air mixture for starting and for operating the engine at sub-normal engine temperatures. The fast idle arrangement usually consists of a cam which forms an abutment for an adjustable stop mechanism on the throttle valve lever of the carburetor and which is connected to and controlled by the choke valve so that the throttle valve is held at a partially opened position for fast idling while the engine is cold. As the engine becomes warmer, the thermostat controlling the automatic choke gradually permits the choke valve to open and the fast idle cam to move to a position at which the throttle valve will close to slow idling position. During normal operation of the engine, the choke valve remains completely open and the fast idle cam in the position to permit the throttle valve to close to slow idle position.

For a time after a warm engine has ceased operation, the thermostat does not exert any force in the direction to close the choke valve or to move the fast idle cam to the cold starting position, but as the engine gradually becomes cold, the thermostat begins to apply force to close the choke valve, gradually increasing said force as the engine becomes cooler. The force tending to close the choke valve also urges the cam to fast idle position. The throttle valve stop means abutting against the cam; however, prevents movement thereof by the thermostat so that the fast idle cam is held in the position assumed during normal warm engine operation and the choke valve, being connected to said cam is prevented from completely closing, until said stop means is withdrawn from said cam by the opening movement of the throttle valve. It is thus seen that before the engine can normally be started, it is essential to depress the accelerating pedal or otherwise open the throttle valve to release the fast idle cam and permit the choke valve to close.

Some later model motor vehicles are provided with a cooperating clutch control and starting mechanism wherein the starting circuit is closed when the clutch pedal is depressed to its most downward limit. By this arrangement, the operator is assured that the vehicle is declutched before the starting circuit is closed, although it is

2

necessary for the operator to actuate the accelerating pedal to crack the throttle valve and to release the fast idle cam and choke valve. It is one of the principal objects of the present invention to combine the foregoing steps into one single starting operation involving only one mechanical movement by the operator.

Another object of the present invention is to provide a simple and highly reliable mechanism for declutching the vehicle, cracking the throttle valve, releasing the fast idle cam and automatic choke and closing the starter circuit.

A further object of the invention is to provide a control mechanism to perform the aforesaid operations, which may be readily adapted to standard motor vehicles without the necessity of making any substantial modifications in the original construction of said vehicles.

Additional objects and advantages will appear from the following description and accompanying drawings wherein a specific embodiment of the present invention is disclosed. The control mechanism forming the subject matter of the present invention is not limited to the embodiment and the modification thereof disclosed herein nor to any particular type of carburetor or internal combustion engine, but is understood to be adaptable to any engine or vehicle in which are included a carburetor having an automatic choke, a fast idle arrangement, clutch and starting circuit, said combination being hereinafter more fully described.

In the drawings:

Figure 1 is a schematic view of an internal combustion engine showing the present control system mounted thereon:

Figure 2 is a schematic view of the present control system showing generally a carburetor, a starting switch, a clutch pedal and an accelerating pedal of a motor vehicle, the relative size of the carburetor and switch to the clutch and accelerating pedals being larger in the drawing than in standard automotive construction, to show clearly the various parts of the present invention; and

Figure 3 is a view of a portion of my mechanism shown in combination with a depressed clutch pedal.

The present control system includes in a motor vehicle an automatic choke, a fast idle arrangement controlled by said choke, a starting switch and a clutch control mechanism in combination with a linkage for actuating the throttle valve, declutching the engine, releasing the choke and fast idle cam and closing the starting switch, all

in a single operation requiring only one simple mechanical movement by the operator. The present invention may be readily understood by referring to the drawings in which Figure 1 illustrates an assembly of the several elements comprising the present invention mounted on a conventional internal combustion engine, wherein numeral 10 designates a clutch pedal shown in its nearly fully depressed position, 11 an accelerating pedal, 12 a starting switch, 13 a starting motor, 14 a battery and 15 a carburetor which for the purpose of illustrating the present invention may be considered conventional, said carburetor being mounted on an intake manifold 16 and connected to said clutch and accelerating pedals by a linkage 18. Referring to Figure 2, the carburetor which is of the downdraft type includes an air horn 20 having mounted thereon an automatic choke 22 consisting of a housing 24, a coiled bimetallic heat responsive element 26 mounted on pin 28, an unbalanced choke valve 30 mounted on shaft 32 and a lever 34 secured to one end of shaft 32, said lever being adapted to be engaged and actuated by the bimetallic element 26. The housing 24 is connected by a conduit 36 to a stove 37 on the exhaust manifold 38 or to some other part representative of engine temperature, and by a port 39 and another conduit 40 to the induction passage on the engine side of the throttle valve. In a cylinder 41 on one side of said housing is a piston 42 connected to lever 34 by rod 43 and adapted to be actuated by suction in conduit 40 to partially open choke valve 30 against the opposing force of element 26 when the engine begins to operate under its own power. The suction actuating piston 42 may be modified to some value less than that in the intake manifold by including a bleed into cylinder 41 such as duct 44 through piston 42. In this arrangement, air indicative of engine temperature is drawn through conduit 36 and housing 24 around element 26 through port 39 and also through duct 44 of piston 42 by the engine suction transmitted through conduit 40. Thus, if the engine is cold at starting, the bimetallic element as shown in the drawings is so expanded that it urges lever 34 to the right and choke valve to its closed position. As the air drawn through the housing 24 becomes warmer, bimetallic element 26 coils upon itself, thereby gradually lessening the force urging the choke valve to its closed position until the free end of said element is completely withdrawn from lever 34. Since choke valve 30 is of the unbalanced type, it tends to open of its own accord and also in response to air flow through the induction passage of the carburetor when the throttle valve posterior thereto has been opened.

The main carburetor body 45, on which air horn 20 is mounted and secured by machine screws 46, contains an induction passage with a main and a boost venturi and a discharge nozzle disposed therein. The main body also contains a conventional accelerating pump in housing 47, a power enrichment means (not shown) and a fuel bowl or float chamber 48 adapted to receive fuel from inlet 49, said main body being mounted on throttle body 50 and secured thereto by machine screws 52. The throttle body is mounted on an intake manifold of an internal combustion engine and secured thereto by bolts inserted in holes 54 of external flange 56 at the lower edge of said throttle body.

A throttle valve 58 is mounted on shaft 60 and actuated by a throttle valve lever 62 on the end

of said shaft, said lever being connected to the accelerating pedal 11 by rod 64, U-shaped lever 66 and rod 68. The closing of the throttle valve is limited when the engine is cold by screw 70 on lever 62 abutting against the periphery of a fast idle cam 72 mounted on stud 73, said periphery being so arranged in stepwise profile that the throttle can be held in various partly open positions while the engine is running at subnormal temperatures. Cam 72 is connected with the automatic choke by rod 74 and lever 76, the lower end of said rod being inserted in a crescent shaped slot 78 of cam 72 and yieldably held in the central portion of said slot during normal operation of the engine by spring 80. The accelerating pump is actuated by the opening movement of the throttle valve lever through rod 82, lever 84 pivoted on screw 86 and rod 88 which connects lever 84 with the piston of the accelerating pump.

The linkage 18 consists of a U-shaped lever 66 pivoted on a pin 114, rod 64 connecting one arm of said lever with the throttle valve lever 62, and another rod 68 connecting the other arm of said lever with the accelerating pedal 11, one end of said lever being adapted to be engaged by a pawl 130 on clutch pedal 10, said pawl being mounted on a stud 134 and urged against a pin 136 by a spring 132. The pin 136 on the clutch pedal is provided as an anchor for spring 132 and as a stop for pawl 130 to prevent said pawl from moving independently of said pedal on the downward movement thereof. One end of lever 66 is provided with a lug 140 which is adapted to be contacted by the free end of pawl 130 when the clutch pedal approaches its lowermost position.

Switch 12 is so positioned in relation to clutch pedal 10 that it is contacted by said pedal or a part thereof when the pedal approaches its lowermost position. A lug 144 having an adjustable screw 146 is provided to engage switch actuating stem 148, the screw being retained in any adjusted position by lock nut 150. If desired, this lug may be dispensed with and instead the switch stem 148 may be so arranged that it will be directly engaged by pedal 10. In this modification adjustable stop means of lug 144 would be mounted on switch 12.

Operation

When an internal combustion engine equipped with the present control mechanism has been stopped after operating under normal engine temperatures, the throttle valve closes and the adjustable screw 70 engages the periphery of cam 72 on one of its lower steps, the choke valve remaining wide open completely independent of the bimetallic element 26. As the bimetallic elements cools, it eventually engages lever 34 and gradually urges choke valve 30 toward its closed position. The closing movement of the choke valve, however, is resisted by cam 72 being held in a fixed position by stop screw 70 engaging one of the lower steps of the cam periphery, though partial closure of said choke valve may be permitted by the yieldable connection between said cam and rod 74 provided by spring 80. Thus, while the engine is cold and the throttle valve closed, the fast idle cam is in slow idle position, and the choke valve is wide open or only partly closed.

In starting the cold engine, the operator depresses clutch pedal 10 until pawl 130 engages lug 140 of lever 138 and, through said lever,

rod 64 and throttle valve lever 62, the operator cracks or slightly opens the throttle valve and withdraws stop screw 70 from the lower steps of the periphery of cam 72, thus permitting said cam to move to fast idle position under the force of the thermostat urging lever 76 and rod 74 upwardly and choke valve 30 to its closed position. If lever 66 is further depressed, lug 140 moves outwardly on pawl 130 until it slips off the end of said pawl, permitting lever 66 to return to its original position and permitting the throttle valve to again close. As the clutch pedal returns to its original position, the underside of lug 140 engages the top side of pawl 130 and forces said pawl from its path. The pawl then returns to its original position against stud 136 under the force of spring 132. While clutch pedal 10 is depressed after the throttle valve has been opened and closed, screw 146 engages stem 148 of switch 12 and closes the starting circuit.

When the engine begins to operate under its own power before the throttle has been opened by the accelerating pedal, suction in the induction passage posterior to the throttle valve draws piston 42 to the left, as shown in Figure 2, thus urging choke valve 30 to a partly open position so that the engine may receive the proper fuel-to-air mixture for fast idling, the throttle valve being held in fast idle position by the higher steps on the periphery of cam 72. The suction in the induction passage also draws the air from stove 37 around the exhaust manifold through conduit 36, housing 24, port 39 and conduit 40. A portion of the air entering housing 24 also passes through calibrated hole 44 of piston 42 and thence into conduit 40, the purpose of said hole being primarily for controlling the amount of suction exerted on piston 42. The air from stove 37 passing through housing 24 gradually heats thermostat 26, causing it to lessen its force urging the choke valve to the closed position until said thermostat completely withdraws from lever 34. Choke valve 30 is then permitted to open wide of its own accord or under the influence of air flow in the induction passage. The opening movement of the choke valve moves fast idle cam 72 to its slow idle position.

If the throttle valve is opened while the engine is operating at subnormal temperatures, the choke valve is urged in the opening direction in opposition to the closing force of thermostat 26 by the air flow in the induction passage, and the cam is simultaneously urged to its slow idle position by the linkage between said cam and choke valve. When the throttle valve is again closed, stop screw 70 may contact the periphery of said cam before the thermostat has had sufficient time to return the choke valve to closed or partially closed position and the cam to its fast idle position. The cam may thus be held in its slow idle position by screw 70 contacting the periphery of said cam. The choke valve, however, is permitted to readjust itself to approximately the proper position for the particular engine temperature by the yieldable connection between cam 72 and rod 74 as provided by slot 78 and spring 80. This slot and spring also permit the choke valve to open even though the cam is continually held in fast idle position by screw 70 during the time the engine is warming up to normal operating temperatures.

From the foregoing description of the operation of the present invention, it can be seen that depression of the clutch pedal to its lower-

most position executes every mechanical manipulation required to start the engine and even to provide the necessary conditions thereafter for normal engine operation during the warming-up period. It is contemplated that other arrangements of elements comprising the present invention than the one shown in the accompanying drawings may be provided without departing from the scope of the present invention; for example, the mechanism for cracking the throttle valve may be actuated by a linkage in series with the starting switch or by a solenoid controlled by the starting circuit; further, a means may be included for rendering the throttle cracking means inoperative when the clutch pedal is depressed after the engine begins to operate under its own power.

I claim:

1. In an internal combustion engine propelled vehicle having a clutch, a clutch pedal, a starting circuit and a carburetor including a throttle valve, a choke and a thermostat for controlling said choke in accordance with engine temperature: a control mechanism comprising a fast idle cam; a linkage connecting said cam and thermostat for controlling the position of said cam in accordance with engine temperature; a throttle valve lever having an adjustable stop thereon for engaging said cam, said stop in cooperation with said cam being adapted to yieldably hold said choke in a partially open position in opposition to the closing force of said thermostat; a starting switch in said circuit; a member actuated by the movement of the clutch pedal for causing said switch to operate; and a linkage including a one-way connection adapted to be connected to said throttle valve lever and to be actuated by said clutch pedal; whereby the operations for declutching the vehicle, opening said throttle valve, releasing said fast idle cam and choke and closing the starting switch may be completed in a single movement by the operator.
2. In an internal combustion engine propelled vehicle having a clutch, a clutch pedal, a starting circuit, an accelerating lever and a carburetor including a throttle valve, a choke and a thermostat for controlling said choke in accordance with engine temperature: a control mechanism comprising a fast idle cam; a linkage connecting said cam and choke for controlling the position of said cam in accordance with engine temperature; a throttle valve lever having a stop thereon for engaging said cam, said stop in cooperation with said cam being adapted to yieldably hold said choke in a partially opened position in opposition to the closing force of said thermostat; a starting switch in said circuit; a member actuated by the movement of the clutch pedal for causing said switch to operate; a linkage adapted to connect said accelerating lever and said throttle valve lever; and a means including a one-way connection adapted to be actuated by said clutch pedal for actuating the linkage between said throttle valve lever and said accelerating lever; whereby the operations for declutching the vehicle, opening said throttle valve, releasing said fast idle cam and choke and closing the starting switch may be completed in a single movement by the operator.
3. In an internal combustion engine propelled vehicle having a clutch, a clutch pedal, a starting circuit, an accelerating lever and a carburetor including a throttle valve, a choke and a

thermostat for controlling said choke; a control mechanism comprising a fast idle cam; a linkage connecting said cam and choke for controlling the position of said cam in accordance with engine temperature; a throttle valve lever having a stop thereon for engaging said cam, said stop in cooperation with said cam being adapted to yieldably hold said choke in a partially opened position; a switch in said circuit; a linkage adapted to connect said accelerating lever and said throttle valve lever; a means including a one-way connection adapted to be actuated by said clutch pedal for actuating the linkage between said throttle valve lever and said accelerating lever; and a second means actuated by said clutch pedal for closing said switch; whereby the operations for declutching the vehicle, opening said throttle valve, releasing said fast idle cam and choke, and closing the starting switch may be completed in a single movement by the operator.

4. In an internal combustion engine propelled vehicle having a clutch, a clutch pedal; an accelerating lever and a carburetor including a throttle valve, a choke and a thermostat for controlling said choke; a control mechanism comprising a fast idle cam; a linkage connecting said cam and choke for controlling the position of said cam; a throttle valve lever having a stop thereon for engaging said cam, said stop in cooperation with said cam being adapted to hold said choke in a partially opened position in opposition to the closing force of said thermostat; a control lever having two arms adapted to be disposed adjacent said clutch pedal; a rod connecting one arm of said control lever with said throttle valve lever; another rod connected to the other arm of said control lever and adapted to be connected to said accelerating lever; and a pawl adapted to be pivotally mounted on said clutch pedal to engage said control lever and to momentarily open said throttle valve, to release said fast idle cam and choke when said clutch pedal is depressed.

5. In the control mechanism defined in claim 4 for a vehicle having the elements recited in said claim, together with a starting circuit; a starting switch for said circuit adapted to be engaged and actuated by said clutch pedal.

6. In an internal combustion engine propelled vehicle having a clutch, a starting circuit and a carburetor including a choke valve, a throttle valve and a fast idle cam; a control mechanism comprising a linkage connecting said choke valve with said cam; a throttle valve lever having a stop thereon for engaging said cam; a clutch pedal; a linkage between said clutch pedal and said throttle valve lever; and a means cooperating with said clutch pedal for closing said starting circuit; whereby the operations for declutching the vehicle, opening said throttle valve, releasing said fast idle cam and choke valve, and closing the starting circuit may be completed in a single movement by the operator.

7. In an internal combustion engine propelled vehicle having a clutch, a starting circuit and a carburetor including a choke valve, a throttle valve and a fast idle cam; a control mechanism comprising a linkage connecting said choke valve with said cam for intercontrolling said cam and choke valve; a throttle valve lever having an adjustable stop thereon for cooperation with said cam; a clutch pedal; a manually operated accelerating lever; a linkage between said accelerating lever and throttle valve lever; a linkage between

5 said clutch pedal and said throttle valve lever; and a means cooperating with said clutch pedal for closing said starting circuit; whereby the operations for declutching the vehicle, opening said throttle valve, releasing said fast idle cam and choke valve, and closing the starting circuit may be completed in a single movement by the operator.

8. In an internal combustion engine propelled vehicle having a clutch, a starting circuit and a carburetor including a choke valve, a throttle valve and a fast idle cam; a control mechanism comprising a linkage connecting said choke valve with said cam for intercontrolling said cam and choke valve; a throttle valve lever having a stop thereon for cooperation with said cam; a clutch pedal; a manually operated accelerating lever; a linkage between said accelerating lever and throttle valve lever; a linkage between said clutch pedal and said accelerating lever linkage; and a means cooperating directly with said clutch pedal for closing said starting circuit; whereby the operations for declutching the vehicle, opening said throttle valve, releasing said fast idle cam and choke valve, and closing the starting circuit may be completed in a single movement by the operator.

9. In an internal combustion engine propelled vehicle having a clutch, a starting circuit, a switch for said circuit and a carburetor including a choke valve, a throttle valve and a fast idle cam; a control mechanism comprising a linkage connecting said choke valve with said cam for intercontrolling said cam and choke valve; a throttle valve lever having an adjustable stop thereon for cooperation with said cam; a clutch pedal; an accelerating pedal; a linkage between said accelerating pedal and throttle valve lever; a means associated with said clutch pedal for imparting movement to said accelerating pedal linkage; and a second means associated with said clutch pedal for actuating said starting switch; whereby the operations for declutching the vehicle, opening said throttle valve, releasing said fast idle cam and choke valve, and closing the starting switch may be completed in a single movement by the operator.

10. In an internal combustion engine propelled vehicle having a clutch, a clutch pedal, a starting circuit and a carburetor including a throttle valve, a choke and a thermostat for controlling said choke; a control mechanism comprising a fast idle cam; a linkage connecting said cam and thermostat for controlling the position of said cam; a throttle valve lever having a stop thereon for cooperation with said cam; a starting switch in said circuit; a means adapted to be actuated by said clutch pedal for opening said throttle valve and releasing said fast idle cam and choke; and a member actuated by the movement of said pedal for closing the switch of said starting circuit.

11. In an internal combustion engine propelled vehicle having a clutch, a clutch pedal, a starting circuit, an accelerating lever and a carburetor including a throttle valve, a choke and a thermostat for controlling said choke; a control mechanism comprising a fast idle cam; a linkage connecting said cam and choke for controlling the position of said cam; a throttle valve lever having a stop thereon for cooperation with said cam; a starting switch in said circuit; a linkage adapted to connect said accelerating lever and said throttle valve lever; a means including a one-way connection

adapted to be actuated by said clutch pedal for actuating the linkage between said throttle valve lever and said accelerating lever for opening said throttle valve and releasing said fast idle cam and choke; and a member actuated by the movement of said pedal for closing the switch of said starting circuit.

12. In an internal combustion engine propelled vehicle having a clutch, a clutch pedal, a starting circuit and a carburetor including a throttle valve, a choke and a thermostat for controlling said choke in accordance with engine temperature: a control mechanism comprising a fast idle cam; a linkage connecting said cam and thermostat for controlling the position of said cam in accordance with engine temperature; a throttle valve lever having a stop thereon for engaging said cam, said stop in cooperation with said cam being adapted to hold said choke in a partially opened position in opposition to the closing force of said thermo-

stat; a starting switch in said circuit; a means adapted to be actuated by said clutch pedal for opening said throttle valve and releasing said fast idle cam and choke; and a member actuated by the movement of said pedal for closing the switch of said starting circuit.
